CLAIM

The ornamental design for a protective headgear, as shown and described.

DESCRIPTION

FIG. 1 is a front left perspective view of a protective headgear in accordance with the current invention;

FIG. 2 is a front right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view taken along line 7-7 of FIG. 5 thereof; and,

FIG. 8 is a left side elevation view taken along line 8-8 of FIG. 5.

The broken lines illustrate the environment in which the protective headgear is used and form no part of the claimed design.
